CONVERTIBLE HACKAMORE BOSAL BIT

Fredrick A. Ray, Van Nuys, Calif.

Application March 27, 1941, Serial No. 385,405

4 Claims. (Cl. 54—6)

My invention relates to a bit of the combination hackamore bosal type and the construction herein illustrated and described is an improvement on the hackamore bit forming the subject matter of U. S. Letters Patent No. 2,225,232 issued to me December 17, 1940.

The principal objects of my present invention are, to generally improve upon and simplify the construction of the bit disclosed in my aforesaid patent, as well as other existing forms of similar bits, to provide a simple and efficient combination hackamore bit that may be used with or without a mouthpiece as desired, to provide improved means whereby mouthpieces may be interchangeably used with the bit, further, to provide a leverage hackamore without a bit, and further, to provide a loose jaw bit with an interchangeable mouthpiece.

Further objects of my invention are, to provide a hackamore bit with an improved sprocket curb and means for connecting the ends of said curb to the cheek pieces of the bit.

With the foregoing and other objects in view, my invention consists in certain novel features of construction and arrangement of parts that will be hereinafter more fully described and claimed and illustrated in the accompanying drawing in which:

Fig. 1 is a side elevational view of my improved hackamore bit and showing the same in position upon an animal's head.

Fig. 2 is an enlarged plan view taken looking in the direction indicated by the arrow 2 in Fig. 1 with parts broken away.

Fig. 3 is a vertical section taken on the line 3—3 of Fig. 2.

Fig. 4 is a vertical cross section taken on the line 4—4 of Fig. 2.

Fig. 5 is an enlarged detail section taken on the line 5—5 of Fig. 3.

Fig. 6 is a side elevational view of a modified form of the bit.

Fig. 7 is an enlarged elevational view of the end of the bosal that is used in connection with the form of bit illustrated in Fig. 6.

Fig. 8 is an elevational view of a latch plate utilized in securing the ends of the bosal to the cheek pieces of the form of bit illustrated in Fig. 6.

Fig. 9 is a plan view of the parts seen looking in the direction indicated by the arrow 9 in Fig. 7.

Fig. 10 is an enlarged detail section taken on the line 10—10 of Fig. 6.

Fig. 11 is an enlarged cross section taken on the line 11—11 of Fig. 6.

Fig. 12 is an elevational view of the upper portion of one of the cheek pieces forming a part of the modified construction illustrated in Fig. 6.

Referring by numerals to the accompanying drawing and particularly to the form of bit illustrated in Figs. 1 to 5 inclusive, 10 designates the main body of one of the two cheek pieces of the hackamore, said body being in the form of a ring, and depending therefrom is an arm 11 that terminates in a smaller ring 12 that provides a point of connection for the bridle rein 13.

Suitably secured by rivets or otherwise to the outer face of each ring-shaped body member 19 is a concha or plate 14 having a convex central portion 15 that provides a cover for the opening in the ring-shaped member 10. Formed integral with the upper portion of each ring-shaped member 19 and at a point opposite the arm 11 is a ring 16 that provides a point of attachment for the end of an adjustable and removable bosal 11, also as a point of attachment for the lower end of the cheek strap 18 of the bridle.

Formed integral with the rear lower portion of ring 16 and directly above the center of the ring-shaped member 10 is a horizontally disposed lug 19 that provides a point of attachment for the curb of the bit, and formed between this lug 19 and the upper portion of member 10 is a recess 20 into which projects one end of a block 21 that is carried by the end of the curb.

The construction just described and particularly the recess 20 provides a pocket adapted to snugly receive a block that is carried by the end of the curb and which block when fitted into said recess below the lug determines the position of the curb with respect to the cheek pieces and prevents the intermediate portion of said curb from swinging vertically in either direction except when actuated by swinging movement of the cheek pieces, with the mouth piece as an axis.

Block 21 is detachably connected to the lug 19 by means of a conventional sprocket chain repair link comprising a plate 22, pins 23 rigidly secured to said plate 22, which pins pass through apertures formed in lug 19 and block 21, a plate 24 that is loosely arranged on the pins 23, and a slotted link 25 which is detachably arranged on the projecting ends of the pins 23 so as to retain the plate 24 thereupon (see Fig. 5).

This link 25 is a conventional bicycle chain repair link and is formed from thin resilient metal with apertures near its ends for the reception of the pins or rivets that connect the chain links and said repair link having a central slit connecting the apertures and extended beyond one

aperture to the end of the link as designated by 25a in Fig. 5, thus permitting the legs of the repair link to be flexed and sprung when applied to or removed from the ends of the link connecting rivets 23.

Connected to the two blocks 21 are the end links of a short section of chain 26 of the sprocket type which forms the curb of the bit. This chain is composed of flat links connected by pivot pins and is flexible in one direction and inflexible in the other direction.

The blocks 21 carried by the ends of the curb chain 26 fit snugly into the recesses 20 below the lugs 19 and such arrangement maintains the curb which is flexible only in one direction, in a definite angular position with respect to the cheek pieces of the bit and particularly the pins that provide points of attachment for the interchangeable mouth pieces.

Enclosing the central portion of this curb chain is a flexible leather piping 27, and formed in the central portion thereof is an opening 28 which permits two or more links at the intermediate portion of the curb to be drawn outwardly from the piping 27, thereby shortening the curb. To maintain the links in their withdrawn position, a cotter pin 29 is passed through the withdrawn links and said pin secured in its inserted position by a thong 30 of leather or the like that is wrapped lengthwise upon the pin and around the links through which said pin passes (see Figs. 2 and 3).

When the curb is properly applied to the cheek pieces of the bit, the ends of the blocks 21 opposite the ends to which the ends of the curb are connected, projects into the notches 20, thus holding the curb in a predetermined position beneath the animal's jaw and said curb is flexible transversely of the jaw but inflexible when swung upward against the jaw.

The means utilized for detachably securing the ends of the bit to the cheek pieces and thereby enabling different bits to be interchangeably used with said cheek pieces, includes vertically disposed pins 31 pivoted at their lower ends to loops 32 that are secured to the lower inner faces of the convex portions 15 of the conchas 14. The upper ends 33 of these pins are reduced in thickness and when in closed position these reduced upper ends occupy notches 34 that are formed in the members 10 of the cheek pieces just above the openings therein.

Mounted for vertical sliding movement in a groove 10b that is formed in the inner face of the upper portion of each cheek piece member 10 and the adjacent inner face of lug 19 is a narrow plate 35 and formed integral with the upper end thereof is a hook 36 which, when said plate is at its lower limit of movement, overlies the upper face of lug 19. This plate overlies groove 10a and the plate 31 therein. A short lip 36a extends from the side of the top of hook 36 and overlies the top of lug 19, thus providing an extension of said hook which may be engaged by the pointed end of a knife blade, a nail or the like, when plate 35 is elevated to release the mouthpiece 39 of the bit. When plate 35 is at its lower limit of movement, its lower end portion overlies the narrow upper end portion 33 of the pin 32, thereby securing the same in upright position as illustrated in Figs. 3 and 4.

The latching plate 35 is retained for sliding movement upon the cheek piece by a plate 37 of thin metal that is secured to the inner face of the upper portion of the cheek piece member 10 75

and the adjacent lug 19. The lower portion of this plate 37 is provided with a notch 38 that permits the upper end of pin 31 to swing into and out of its closed position when the retaining plate 35 is elevated. Notches 34 and 38 coincide with each other, with the lower portion of plate 35 same as seen in Fig. 4.

In Figs. 3 and 4 I have shown the end portion 39 of a bit positioned upon the pin 31 and in Fig. 10 4 dotted lines a show the bit-carrying pin swung away from the cheek piece so as to enable the end of the bit to be applied thereto or removed therefrom.

In the form of bit just described, the cheek 15 pieces when actuated by a pull on the bridle reins will be partially rotated on the axis formed by the mouthpiece 39, and as such action takes place the entire curb being inflexible at right angles to its length, will swing upwardly against the under 20 side of the animal's jaw. The length of the curb may be readily adjusted by manipulating the intermediate portion of the chain 26 through the opening 28 in the flexible piping 27 and the ends of said curb may be readily detached from the 25 cheek pieces by removal of the sprocket repair links that connect the ends of the curb to the lugs 19. The pivoted or swinging pins 31 provide simple and convenient means for interchangeably using various mouthpieces with the cheek pieces 30 of the bit and said pins are retained in closed positions by the sliding members 35.

The modified construction illustrated in Figs. 6 to 12 inclusive combines a bosal and a conventional curb and the bosal which is adjustable 35 in length is detachably connected to the upper portions of the cheek pieces. This form of bosal may be used with either an interchangeable or non-interchangeable bit.

In this construction, the upper portions of the 40 cheek pieces 10a terminate in rings 40 and projecting downwardly and rearwardly from the lower portions of said rings are lugs 41 that form points of attachment for the ends of a conventional curb 42.

45 The bosal comprises a strap 43, the ends of which are adjustably connected to separately formed elongated pieces of leather 44, the lower end portions 45 of which are substantially circular in form. Secured by rivets or otherwise on the outer face of each member 44 is a metal plate 46, the lower end portion 47 of which extends downward onto the lower portion of the circular lower end 45 of member 44, and formed on this lower portion of said plate is an outwardly projecting circular flange 48. Projecting outwardly from the lower portion 47 of plate 46 and centrally arranged within the ring 48 is a stud 49.

A narrow horizontally disposed strip 50 of the material in plate 46 above the lower portion 47 is pressed outwardly so that it occupies a vertical plane a slight distance offset from the plane occupied by the portion 47 and formed through the lower portion of this offset strip 50 just above the flange 48 is a horizontally disposed slot 51. A portion of the metal in plate 46 at the outer end of strip 50 is bent outwardly and thence rearwardly to form a hook 52 that is substantially U-shape in horizontal section.

70 When the bosal constructed as described is applied to the cheek pieces of the bit, the end portions 45 of the members 44 are disposed inwardly from the rings 40 and the rings 48 on the members 47 project through said rings 40 as illustrated in Fig. 11. Thus the ends of the bosal are

rotatably connected to the upper ends of the cheek pieces.

To detachably connect the ends of the bosal with the rings 49 on the upper ends of the cheek pieces, latch plates 53 are provided with substantially inverted L-shaped slots such as 54, the lower ends of the vertical legs of which slots are slightly offset to form stud receiving bearings 55, and at the point where the vertical legs of said slots join the horizontal legs, the slots are slightly enlarged as designated by 56 for the accommodation of the heads of the studs 49.

After the circular flange 48 has been inserted through ring 40, plate 53 is positioned and manipulated so as to cause stud 49 to pass through the enlarged portion 56 of slot 54, after which said plate 53 is elevated until the shank of the stud 49 enters the bearing 55 at the lower end of the slot, thus maintaining the parts 40 and 47 in assembled relation and with plate 53 overlying the flange 48.

Plate 53 is now slightly rotated so as to position the upper right hand corner thereof beneath the hook 52 and when so positioned the horizontally disposed upper portion of the slot 54 registers with the slot 51 in the plate 46 and said coinciding slots receive the lower portions of the cheek strap 18a of the bridle, and as a result the plate 53 is maintained in proper position on the lower portion of plate 46.

Integrally secured to the outer faces of the rear portions of the plates 53 to the rear of and below the slots 54 therein are loops 57 that provide points of attachment for a conventional "tie down."

In the event that it is desired to use the hackamore structure including the bosal, the cheek straps 18a and head stall to which the cheek straps are connected, the cheek pieces 10a are removed from the plates 47 and a flexible member such as a strap, rope or chain, connects the loops 57 to function as a curb. In the event that it is desired to provide a hackamore without a bosal, the strap 43 which is detachably connected to the members 44 and which passes over the animal's nose, is removed.

Thus it will be seen that I have provided a relatively simple, practical and inexpensive convertible hackamore bit combination that may be used either as a leverage hackamore or with a snaffle bit or as a halter without a bit and which combination is particularly suitable for the breaking of colts.

Further, the hackamore bit combination may be readily converted into a loose jaw bit without the bosal and the interchangeable mouthpiece fea-

ture enables the use of any desired width or shape of mouthpiece without the necessity and expense of providing anything more than the extra mouthpieces which are capable of being interchangeably used with the bit.

Further, my improved hackamore bit combination provides for the functions of a conventional bosal under the chin with the leverage advantage of the cheek pieces of the bit in addition to the conventional loose chain curb, both of which are encased in leather piping for the humane protection to the horse.

In addition, the hackamore bit combination illustrated in Fig. 6 provides a number of variations which are highly effective in the humane control of horses while being ridden, and the construction also includes provision for the use of a tie down for high head horses and applicable to either English or Western equipment.

It will be understood that minor changes in the size, form and construction of the various parts of my improved convertible hackamore bosal bit, may be made and substituted for those herein shown and described, without departing from the spirit of my invention, the scope of which is set forth in the appended claims.

I claim as my invention:

1. In a hackamore bit, a pair of cheek pieces, means carried by said cheek pieces for detachably securing a bit, an eye on the upper portion of each cheek piece, a bosal detachably connected to the eyes of the two cheek pieces, lugs projecting rearwardly from the lower rear portions of said eyes, there being recesses formed in the cheek pieces below said lugs, blocks fitting snugly within said recesses, releasable connections between said blocks and lugs and a curb connected to said blocks.

2. A hackamore bit as set forth in claim 1 and which curb is flexible in one direction longitudinally and inflexible in the other direction.

3. A hackamore bit as set forth in claim 1, which curb is flexible in one direction longitudinally and inflexible in the other direction and means for varying the length of said curb.

4. In a hackamore bit, a pair of cheek pieces, means carried by said cheek pieces for detachably securing a bit, means on said cheek pieces providing points of attachment for a bosal and cheek straps, lugs projecting rearwardly from the upper portions of said cheek pieces, there being recesses formed in said cheek pieces below said lugs, a flexible curb, the ends of which are seated in said recesses and detachable connections between said lugs and the ends of said curb.

FREDRICK A. RAY.
